UNITED STATES PATENT OFFICE.

ERNEST A. BICKFORD, OF WORCESTER, MASSACHUSETTS.

SLIPPER-SOLE.

1,129,160.

Specification of Letters Patent.

Patented Feb. 23, 1915.

Application filed March 19, 1914. Serial No. 825,911.

To all whom it may concern:

Be it known that I, ERNEST A. BICKFORD, a citizen of the United States, residing at Worcester, in the county of Worcester and State of Massachusetts, have invented a new and useful Slipper-Sole, of which the following is a specification.

This invention relates to a slipper sole of the type which have been sold heretofore as a separate article of manufacture for the purpose of having an upper applied thereto by hand.

One of the objects of this invention is to provide a construction of this character to which the upper, although capable of being applied by hand in a most convenient way, can also be applied by machine, so that the complete slipper can be sold as an article of manufacture if desired instead of the separate sole, but it is to be understood that the sole itself also constitutes a separate article of manufacture which can be sold in the same manner as heretofore.

The invention also has for an important object thereof the provision of means for attaching the upper so arranged that none of the parts or materials attaching the upper to the sole come into a position to wear, and so that the edge of the sole after the attachment is completed will show as a smooth finished welt.

The invention also involves improvements in details of construction as will appear hereinafter.

Reference is to be had to the accompanying drawings, in which—

Figure 1 is a plan of a slipper sole constructed in accordance with this invention showing one stage of the manufacture; Fig. 2 is a bottom plan view of the same; Fig. 3 is an enlarged sectional view on the line 3—3 of Fig. 1 showing this stage of manufacture; Fig. 4 is a top plan view of the sole showing a later stage in the manufacture; Fig. 5 is an enlarged sectional view of the same on the line 5—5 of Fig. 4; Fig. 6 is a plan of the complete slipper sole ready for the attachment of the upper; and Fig. 7 is an enlarged sectional view of the same on the line 7—7 of Fig. 6 showing the upper 50 in addition.

The slipper soles known ordinarily as "lamb's wool", satin, and the like, soles have been open to a serious defect ever since they have been on the market. This 55 defect is due to the fact that the threads by which the upper is attached to the sole necessarily come directly into a position on the outer edge in which they wear. On account of this difficulty they have necessarily 60 been made of comparatively cheap materials because there was no use in using the highest grade materials when there was no way of strengthening them at this, their weakest point. In spite of this serious defect the 65 welt effect is so desirable in the appearance of the sole that an important industry has been maintained on this type of sole for several years and numerous patents have been taken out relating to the subject. 70

I have discovered that by an extremely simple arrangement, not involving additional expense, and in fact permitting the manufacture in a more economical manner by machinery, this entire difficulty is done 75 away with, so that soles may be made of as high grade materials as can be obtained, and there will be no necessity for the attaching stitches to come to wear and thus destroy the value of the high grade materials. It also possesses the additional advantage that the upper can be attached by machinery if desired so that complete slippers can be sold on the market manufactured entirely by machinery and having 80 85 wearing qualities greater than the previous hand attached constructions. For this purpose I take as usual a sheet of leather, pasteboard, or other comparatively stiff material and cut it out to form a body portion *a*. 90 This may be provided with a lining on the top surface or not as desired, but on the bottom surface is pasted or otherwise secured an outer covering *b* comprising a thin sheet of leather, the flesh side being secured 95 to the body portion preferably so that the grain side shall constitute the wearing surface. This is cut out to the same shape as

2

the body portion but extends beyond it all around a distance sufficient to enable it to be turned over the edge as will appear. This sole with its covering lying flat is turned bottom side up and an attaching strip preferably in the form of a piece of tape *c*, is secured at a distance about half way between the edge of the body portion *a* and the edge of the covering *b*. The line of stitches *d* by which this tape is secured follows the stiff edge of the body portion and in practice that edge can be used as a guide in sewing those parts together. This line of stitches also is as near as possible to the outer edge of this tape. In other words, at this stage of the operation as shown in Figs. 1, 2 and 3 this tape extends inwardly along the bottom of the sole from its attaching line of stitches *d*. The next step in the operation is to turn this part of the slipper, that is, to bend the outer edge of the covering *b* up over the edge of the body portion *a* and cement or otherwise secure it to the top surface thereof as shown in Figs. 4 and 5. The result of this is that the line of stitches *d* comes just inside the edge of the body portion *a* and the attaching strip *c* extends outwardly from it and on account of the shape of the sole projects upwardly all around as indicated in Fig. 5. In this way it will be seen that a smooth surface is secured around from the bottom to the top of the sole at the edge and all of this surface is formed by the grain surface of the covering *b*. Moreover, the attaching strip is secured by the line of stitches *d* which pass through the covering *b* only and which is located inside the attaching strip, so that the latter piece covers it and prevents these stitches from coming to a position in which they will wear, and leaves the attaching strip so that when the upper *e* is applied that will also be attached by a series of stitches *f* which do not come to a position to wear.

Before the upper is applied of course, the inner lining *g* is applied, and it is shown as of lamb's wool arranged to overlap the inner edge of the covering *b* so that it will not show. In this way the edge of the hide which forms the base of the lamb's wool inner lining will generally come substantially flush with the inner edge of the attaching strip *c* so that they form practically a continuous surface and the attaching strip extends upwardly almost directly from the edge of the lamb's wool lining. The upper in this case can be attached by machinery because no peculiarity in the sewing is required and it is to be applied directly to the attaching strip *c* which extends upwardly from the sole and is preferably free from the other parts and capable of being sewed through without any difficult manipulations of the parts.

As the wear all comes on the outer covering *b* and none of the stitches come to wear it will be seen that this outer covering can be made as durable as desired and the length of life of the sole and slipper will depend upon its durability. Therefore a sole having much longer life can be made more economically and advantageously than has been the case with those constructions in which the stitches pass through the edge of this outer covering and limit the life of the whole article.

Although I have illustrated and described only one specific embodiment of the invention I am aware of the fact that many modifications can be made therein and especially that other attaching strips than tape and other combinations of materials for the body portion and outer covering can be employed without departing from the scope of the invention as expressed in the claims. Therefore I do not wish to be limited in these respects, but

What I do claim is:—

1. As an article of manufacture, a slipper sole comprising a body portion, an outer covering attached to the bottom of the body portion and being turned inwardly over the edge of the body portion and secured to the top thereof, and an attaching strip arranged to have an upper secured thereto, secured along a line to said inwardly turned portion of said covering and projecting upwardly at the outside of said line.

2. As an article of manufacture, a slipper sole comprising a stiff body portion, a flexible covering larger than the body portion attached to the bottom of the body portion and being turned inwardly over the edge of the body portion and secured to the top thereof, and an attaching strip arranged to have an upper secured thereto, secured along a line to said inwardly turned portion of said covering and projecting upwardly at the outside of said line, whereby the upwardly projecting part of the strip is located entirely outside said line and concealing the same.

3. As an article of manufacture, a slipper sole comprising a body portion, a leather outer covering having the flesh side secured to the bottom of the body portion and being turned inwardly over the edge of the body portion and secured to the top thereof and a tape arranged to have an upper secured thereto, sewed to the grain side of the outer covering along a line and projecting upwardly at the outside of said line.

4. As an article of manufacture, a slipper sole comprising a body portion, a leather outer covering having the flesh side secured to the bottom of the body portion and being turned inwardly over the edge of the body portion and secured to the top thereof, a tape sewed to the grain side of the outer

covering along a line and projecting upwardly at the outside of said line, whereby the upwardly projecting part of the tape is located entirely outside of said line and conceals the same when in use, and an upper 5 sewed to the outer edge of said tape and projecting upwardly therefrom.

In testimony whereof I have hereunto set my hand, in the presence of two subscribing witnesses.

ERNEST A. BICKFORD.
